H. BRUNDAGE.
PAPER FILE AND BINDER.
APPLICATION FILED DEC. 10, 1920.
1,423,076.

Patented July 18, 1922.

Inventor
Harry Brundage
By his Attorney
Eugene Boach

UNITED STATES PATENT OFFICE.

HARRY BRUNDAGE, OF SAN FRANCISCO, CALIFORNIA, ASSIGNOR TO GEORGE W. KOERNER, OF NEW YORK, N. Y.

PAPER FILE AND BINDER.

1,423,076.

Specification of Letters Patent. Patented July 18, 1922.

Application filed December 10, 1920. Serial No. 429,620.

To all whom it may concern:

Be it known that I, HARRY BRUNDAGE, a citizen of the United States, and a resident of San Francisco, county of San Francisco, 5 and State of California, have invented certain new and useful Improvements in Paper Files and Binders, of which the following is a specification.

This invention has as its main object to 10 provide a portable file in which perforate sheets of paper may be neatly and compactly preserved in condition for ready reference.

Another object is to provide means whereby the file prongs may be securely clamped 15 when in an engaged position, but which permits easy and rapid insertion or removal of individual papers.

A further object is to provide means facilitating the transference of any desired 20 portion of the papers en bloc, and without disarrangement of those remaining.

A still further object is to provide means for clamping the papers on the file prongs.

These and other analogous objects are attained by the novel construction, combination and arrangement of parts hereinafter described and shown in the accompanying drawings, forming an essential part of this disclosure, and in which:—

30 Figure 1 is a perspective view showing the file and binder extended, the engaging prong elements being clamped, and indicating in broken lines the transfer device in operative position.

35 Figure 2 is a similar view of the same, exhibiting the purpose of the invention.

Figure 3 is a fragmentary sectional view taken on line 3—3 of Fig. 1, and drawn to an enlarged scale.

40 Figure 4 is a plan view of the parts shown in Figure 3.

Figure 5 is a sectional view taken on line 5—5 of Figure 3.

45 Figure 6 is a fragmentary sectional view taken on line 6—6 of Figure 1.

Figure 7 is a fragmentary side view of the engaged ends of the file and transfer prongs, drawn to a further enlarged scale.

50 Figure 8 is a plan view of the clamp used to hold papers on the file prongs.

Referring to the drawings in detail, the numeral 10 designates a pair of stiff cover plates preferably made of heavy paste-board and covered with flexible textile fabric, this

fabric acting as hinges at the folding lines 55 11, which connect with the central element or backing plate 12, similar in construction to the plates 10.

Secured centrally of the center plate, upon its inner side, by rivets 14, is a thin metallic 60 plate 15, bent at right angles outward along its edges forming uprights 16 and 17, the latter of which is extended and rolled into a cylindrical bead 18 enclosing a rod 19 in the manner of a hinge. 65

The extending elements of the rod 19 are bent to present a pair of arcuate parallel curves, constituting the filing prongs 20 terminating in straight ends 21 containing central drilled openings 22. 70

Formed in the edge of the opposite upright 16 are a pair of recesses, or slots 23 receptive of the prong ends 21 when turned downward to enter the same.

An elongated spring plate 25 is held by 75 rivets 26 to the outer side of the upright 16, the plate having curved ends and offset portions 27 adjacent the rivets.

Interposed between the spring plate and upright is a slide 28 having a central longitudinal slot 29, the length of the slot being in excess of the distance between the rivets 27 which pass through it. The extreme ends of the slide 28 are bent forward forming stops 30 and 31 adapted to make contact 85 with the ends of the upright 16 thereby limiting the movement of the slide.

The upper edge of the slide is bent outwardly and then curved reentrantly forming an open U shaped guard 32, its upper edge 90 being in register with the top edge of the upright 16, and in which are received the ends 21 of the file prongs, the same passing through slots 33 in the upper portion of the guard when the slide is pushed so that 95 the stop 30 makes contact with the end of the upright, and when the guard and slide are moved to their other extreme position, the ends 21 are securely locked in the guard, and it is to be noted that the slide is frictionally held in either position, due to the spring plate 25.

The foregoing structure constitutes the simpler form of file and, as will be seen, is effective for its purpose, the sheets or leaves 105 of paper or other material to be filed, having been perforated, are placed in position upon the connected file elements 20, which are

then turned downward, through the slots 33, into the recesses 23 and the slide moved to engage their ends in a manner easily understood.

5 In order to shift any considerable number of papers from the file in a pack the following additional device is used.

Secured on the inner side of the cover plate adjacent the locking device, is a metallic plate 35, held by rivets 36 and having its outer edge rolled into a bead 37 loosely containing a wire or rod 38, bent to present substantially straight parallel fork elements 39 turned outwardly at their ends and reduced in diameter, presenting pin-like extremities 40 adapted to be received within the openings 22 of the prongs when brought into engagement, as best shown in Figs. 2 and 7, a coiled spring 41 encircling the rod 38 and operatively engaging one of the fork elements 39 and plate 10, acting to press the pins or spurs 40 into the ends 21 and maintain them in engagement.

When these elements are not required, one of the rods 38 is engaged below a clip 42, held by a rivet 43 to the cover plate, near the end of the rod, which, as will be understood, is sufficiently resilient to permit springing inward from below the clip when desired.

In order to hold the loose papers compactly on the file prongs, as shown at the right of Fig. 2, the clamping device disclosed in Fig. 8 is used.

35 This device is comprised of a loose metal plate 45, having a beaded edge 46 and containing openings 47, the material removed from the openings being formed into rolls 48 used as bearings for a rod 49 bent into a 40 central loop 50 between the bearings to be used as a handle, the ends of the rod being turned in the same plane as the loop, forming fingers 51.

45 Circular openings 52 are formed through the plate, the same being receptive of the file prongs 20 when the plate 45 is pressed thereover and the elements 51 turned outward, away from the openings 52 by properly manipulating the handle 50.

50 When the plate has been pressed into position on the paper, the handle is turned as shown, the fingers 51 forcing the prongs outward, causing them to bind in the openings and clamp the papers firmly in position.

55 From the foregoing it will be seen that a neat appearing and effective file and binder has been disclosed capable of fulfilling its purposes and that the same is of simple and inexpensive construction.

60 Having thus described my invention and set forth the manner of its construction and

use, what I claim as new and desire to secure by Letters Patent, is:—

1. A file comprising a plate, uprights formed at the lateral edges of said plate, a pair of arcuate prongs, a rod integral with said prongs, said rod being hinged in one of the uprights, the other upright having recesses receptive of the ends of said prongs, a slide movable on the outer side of the last named upright, a locking means formed with said slide into which the prong ends enter, stops for said slide and means for resiliently holding said slide on the upright. 75

2. A file comprising a pair of covers, a backing plate hingedly engaged therebetween, a metal plate fixed on said backing plate, uprights formed with the lateral-edges of said metal plate, a pair of prongs hinged in one of said uprights, means on the other upright for securing the ends of said prongs when entered therein, a fork hinged to one of said covers, outturned spurs at the ends of said fork, said spurs being engageable in openings in the ends of said prongs and a spring adapted to cause such engagement. 80

3. A file comprising a pair of covers, a backing plate hingedly engaged therebetween, uprights on said plate, a pair of curved prongs hinged to one of said uprights, said prongs having longitudinal openings at their free extremities means on the other of said uprights for engaging or disengaging said prongs, a fork hinged to the cover adjacent the last named upright, 90 said fork having parallel elements terminating in spurs turned at an angle, said spurs being engageable in the mentioned openings in said prongs, a spring arranged to force said spurs towards said prongs and a clip 100 on said cover whereby said fork may be retained thereagainst.

4. A file comprising a pair of rigid covers, a rigid backing plate hingedly connecting said covers, uprights extending in parallel from said plate, one of said uprights having a rolled edge, file prongs pivoted in said edge adapted to extend over the other upright and enter recesses therein, a guard receptive of the ends of said prongs slidably mounted 110 on the last named upright, stops limiting the action of said guard, spring means for frictionally holding said guard in adjustment, a fork pivoted on one of the covers, means co-operative between said fork and prongs whereby they are adapted to form continuous guides for articles disposed thereon and a clip for holding said fork when not in use. 115

In testimony whereof I have signed my name to this specification.

HARRY BRUNDAGE.
